[57] CLAIM

The ornamental design for a sewing cabinet, substantially as shown and described.

DESCRIPTION

FIG. 1 is a front perspective view of the sewing cabinet showing our new design;

FIG. 2 is a front perspective view of the sewing cabinet with the front door open and the sewing machine supporting platform extended;

FIG. 3 is a front elevational view of the sewing cabinet shown in FIG. 1;

FIG. 4 is a right side elevational view thereof;

FIG. 5 is a top plan view thereof;

FIG. 6 is a rear elevational view thereof;

FIG. 7 is a left side elevational view thereof; and

FIG. 8 is a bottom plan view thereof.
